UNITED STATES PATENT OFFICE.

WALTER T. JANNEY, OF PHILADELPHIA, PENNSYLVANIA.

CENTRIFUGAL CASTING MACHINE.

Application filed August 7, 1922. Serial No. 580,162.

To all whom it may concern:

Be it known that I, WALTER T. JANNEY, a citizen of the United States, residing at Philadelphia, in the county of Philadelphia and State of Pennsylvania, have invented certain new and useful Improvements in Centrifugal Casting Machines, of which the following is a specification.

My invention relates to centrifugal casting machines.

An important object in view is to provide a device of this character with means for reliably and yet yieldingly holding the lid and mold in operative engagement with each other during the casting operation, so that the sudden expansion of the mold which invariably takes place when the mass of molten metal is suddenly poured into it, will not subject the parts to undue strain, and will not in any way unfavorably affect the perfect operation of the machine.

Another object is to provide a centrifugal casting machine having means for holding the lid rigid on the machine, and means for holding the mold in yielding engagement with the lid.

Still another object is to provide mechanism permitting the employment of electro-magnetic means for this purpose.

Another object is to provide means for the employment of centrifugal force for pressing the mold into yielding engagement with the lid.

A further object is to provide a mold or die formed in sections and having a suitable carrier and lid movable toward and from each other, between which carrier and lid the mold is held, said parts being all arranged to employ the movement of the carrier and lid toward each other to hold the sections of the mold in operative relation to each other, and means for yieldingly pressing the carrier and lid, the one toward the other.

Still another object is to provide a lid having annular slots for the escape of the excess metal poured into the mold.

Other objects will appear in the subjoined description.

An important feature of the invention consists of a revoluble basket having a lid rigidly held thereon against outward movement; and a mold carried inside the basket; and means including centrifugal force, or electro-magnetism, for yieldingly holding the mold in engagement with the lid.

The invention consists in certain novel features of construction and arrangement of parts, as will be hereinafter described and claimed, reference being had to the accompanying drawings, in which;

Fig. 1 is a sectional view of a form of my device in which centrifugal force is employed to press the mold and lid together.

Fig. 2 is a plan view of the centrifugal mechanism and pulley.

Fig. 3 is a side elevation of the plunger used with this form of the device.

Fig. 4 is a sectional view of a form of my device in which I employ electro-magnetism to hold the sections of the mold in yielding engagement with each other and with the lid.

Fig. 5 is a plan view showing the electro-magnets and the pulley on which they are mounted.

Fig. 6 is an end elevation of the form of the device illustrated in Figs. 1 and 4.

Fig. 7 is a plan view of the lid used with this form of the device.

Fig. 8 is a sectional view of Fig. 7.

Fig. 9 is an end view of the mold or die, the mold being shown in this view as formed in two sections spaced from each other for better illustration.

Fig. 10 is a side elevation of Fig. 9; and,

Fig. 11 is a broken sectional side elevation of one of the castings formed in the mold illustrated in Figs. 9 and 10, which is the same form of mold shown in Figs. 1 and 4.

Attention is called in the outset to the fact that centrifugal force has been employed to yieldingly hold the lids on centrifugal casting machines, which arrangement works very well when the molds are held sufficiently upright to hold the lids in operative position on them by gravity till the machinery is speeded up sufficiently to make the centrifugal mechanism grip the lids. But, for the majority of castings, the molds should be disposed horizontally, in which position gravity will cause the lids to fall off the molds before the machine starts revolving, unless other means be provided for holding them in operative position till the centrifugal mechanism has been caused to revolve with sufficient rapidity to grip the lids.

With my arrangement, no such difficulty can exist, even when centrifugal force is employed, as shown in Fig. 1, to hold the lids and molds in operative relation to each other, for in my construction, instead of the

lid being held on the mold, the mold is yieldingly held against the lid—is held in a casing which serves as a guide for its movements, so that when a horizontal mold is standing still, the mold will have no disposition to move out of engagement with the lid, but even if it did, the fact that the mold has guided movement relatively to the lid, would cause it to certainly move back into proper engagement therewith, whether pressed by centrifugal force or any other force whatsoever: so that the great advantage of having a stationary lid cooperating with a movable mold, becomes more and more apparent.

Referring further to the drawings, the numeral 1 indicates a housing having a large central opening 2 at its forward end, and at its inner end an integral sleeve 3 into which is cast a long bearing 4, which supports a hollow shaft 5, having at its inner end inside the housing 1, a heavy flange 6, and beyond the sleeve 3 of the housing, a pulley 7 rigidly held thereon. A basket 8 is rigidly held on the flange 6 by stud bolts 9, and loosely fitting inside this basket is a mold cup 10 which serves as a container for the two halves of the split die or mold 11, it being understood, of course, that the die 30 may be divided into more than two sections if desired.

A lid 12 holds the cup 10 and the die 11 in the basket 8.

The lid is provided on its inner side with an annular inclined face 13, and the bottom of the cup 10 has a correspondingly inclined face 14. The two ends of the sectional mold or die are frusto-conical in shape, with their annular inclined faces 15 and 16 adapted to fit the annular faces 13 and 14 of the cup 10 and the lid 12.

The length of the die relatively to the depth of the cup is always such that the cup and lid cannot quite touch each other.

When the plunger is forced toward the mold, the piston 21 at the inner end of the plunger presses the cup 10 outwardly, and with it the sectional die 11, which in turn presses the lid into engagement with the lugs 50 18 at the open end of the basket 8.

The lid is provided with a central opening 12^a and annular slots 17, the exterior diameter of which is equal to the interior diameter of the casting 11^x to be formed.

The basket is provided with four inwardly extending lugs 18 behind which the four outwardly projecting lugs 19 are received, as more clearly illustrated in Fig. 6, which figure refers to the forms of the device illustrated in Figs. 1 and 4.

In the form of the device illustrated in Fig. 1, the opening in the hollow shaft 5 is suitably enlarged at its inner end to receive the plunger 20 which has a piston 21 at its inner end and a smaller piston 22 spaced

therefrom. The stem of the plunger 20 carries a compression spring 24 which is received around said stem between the small piston 22 and the thrust plate 23^a, which is rigidly secured to the shaft 5 and has a central opening 26 adapted to snugly receive said stem 20, by which arrangement the plunger has imparted to it by the spring a tendency to always move outwardly.

In the form of the device illustrated in Fig. 4, I have provided electrical means for pressing the mold into engagement with the lid. In this form of the device the plunger 20 has an integral extension 31, which has a soft iron plate rigidly secured to its projecting outer end. The pulley 33 which is rigidly mounted on the hollow shaft 5, carries on its hub a copper ring 34 which is insulated from said hub by a fibre collar 35. This ring through carbon brush 36 and wire 37 is in continuous contact with a source of direct current energy. The pulley 33 also has rigidly mounted thereon four soft iron cores 38 which are wound with insulated wires 39 each leading from the copper ring 34. These wires are wound in such a manner that the opposite cores 38 will form magnetic poles of opposite polarity when a direct current is passed into the ring 34 and thence through the wires 39 forming the coils 40 around the cores, and thence returning to the battery through the frame of the machine. When a direct current is passed from the ring 34 through the coils 40, the cores 38 form a four-pole magnet, and as the lid is made of magnetic material, it is drawn toward the magnetic poles which causes the plunger 20 to press the cup 10 and the mold carried thereby.

In the form of the device shown in Fig. 1, centrifugal force is employed to operate the plunger 20. The arrangement is very simple; the plunger being provided with an integral extension 59 which is pivoted at its outer projecting end at 60 to the inner ends of the centrifugal levers 61 which are fulcrumed at 62 to ears 63 carried on the outer end of the hollow shaft 5. These levers have at their outer free ends the weights 64. The centrifugal levers are preferably bifurcated at their inner ends, as shown in Fig. 2 of the drawings, to cause them to pull equally on each end of their respective pivots. Motion is imparted to the device by the pulley 7.

In Fig. 6 I have shown a front-end elevation of the form of the device illustrated in Figs. 1 and 4, with the lid in operative position, the lugs 19 thereof being passed in behind the inwardly extending lugs 18 of the revoluble basket 8, and the annular slots being arranged to form a casting of the form shown in Figs. 1, 4, and 11. Fig. 7 shows the lid removed from the basket in order to make its construction perfectly plain when taken in connection with Fig. 8, which

shows the same in section. Figs. 9 and 10 show an end view and a side elevation respectively of the split mold or die illustrated in Figs. 1 and 4, the parts being shown separated to accentuate the fact that the die is made in sections; and Fig. 11 shows one of the castings made in this mold. From this view it will at once be seen that if the mold were not made in sections, the casting could 10 not be removed from it without destroying the mold.

The operation of my device is as follows:—

Referring first to Fig. 1, and assuming 15 that the parts are disassembled, with the plunger 20 forced to the farthest position to the right by the spring 24, the cup 10 is placed in the basket 8; then the sections of the split die are assembled in the cup; then 20 the lid 12 is slipped into the open end of the basket into engagement with the split die and is turned to bring its lugs 19 behind the lugs 18 of the basket; the machine is then caused to rotate rapidly by means of 25 a power belt passed around the pulley 7. The centrifugal mechanism then operates to force the piston 21 against the bottom of the cup 10 pushing the cup and the die 11 and the lid outwardly till the lugs 19 of 30 the lid are firmly pressed against the lugs 18 of the basket; the molten metal is then poured into the mold through the opening 12^a at the centre of the lid, which opening is smooth and true and therefore does not 35 bump or jar the tile spout through which the metal is poured. The metal takes the form of the mold, and if there be any excess metal it passes out through the annular slots 17 and is caught in the casing 1.

40 As the mold is rapidly revolved preparatory to pouring the molten metal, the air is exhausted from the mold through the openings 17 of the lid which causes a continuous current of air to be sucked in through the 45 central opening 12^a. But when the spout is entered into this central opening and practically fills it, the suction operates on the molten metal in the spout to draw it very rapidly into the mold, causing it to be 50 come more quickly and more evenly distributed over the entire inner surface of the mold, which is a decided advantage.

The pressure of the piston 21 against the 55 cup 10 presses the die between the cup and the lid with the inclined faces of both cup and lid in engagement with the inclined faces of the die, so that however much the die may expand from the heat of the molten metal, or however sudden the expansion 60 may be, the sections of the die will be yieldingly held in firm operative relation to each other by reason of the resiliency of the centrifugal force. For the same reason the expansion of the die in a longitudinal di- 65 rection will be permitted by the plunger 20.

When the metal has been poured, the machine is stopped, and the centrifugal pressure imposed upon the cup 10 through the piston 21 is of course relieved, which permits the plunger 20 to be forced to the right by 70 the spring 24; this in turn relieves the pressure against the lid and permits it to be easily removed from the basket; the casting and the die are then removed from the cup by a pair of expanding tongs and the sections of the die are jarred loose from the casting, and the parts are ready for the operation to be repeated.

The easy and quick removal of the lid provided for in my construction permits the 80 machine to be operated, time after time, in rapid succession.

The thickness of the wall of the casting is determined by the position of the curved slots 17, so that only a differently slotted 85 lid is necessary to produce a casting with a thicker or a thinner wall.

In the form of the device illustrated in Fig. 4, the operation is the same as in Fig. 1, except that in Fig. 4 electro-magnetism is 90 employed instead of centrifugal force to press the plunger against the cup 10.

Special attention is now called to a great advantage which I gain by making the mold movable relatively to the lid, instead 95 of making the lid movable relatively to the mold as has been heretofore done. Take for instance the form of the device illustrated in Fig. 4 of the drawings: if the electrical mechanism were arranged to operate directly on the lid of the device, it would probably have to be so close to the lid, that the part corresponding to the plate 32 would become so heated, when the mold was used 100 continuously, time after time, that said part would cease to be magnetic, and would at that point become inoperative. But with the arrangement shown, the plate 32 can be moved as far as may be desired from the mold, so that it will never become over-heated.

Still again, take the form of the device shown in Fig. 1, which permits the centrifugal weights to be so far removed from the hot metal, that they never become over-heated, and the parts are not in danger of binding, and can be easily kept oiled, whereas in the ordinary construction in which the lid of the mold is directly pressed by centrifugal mechanism, said mechanism necessarily becomes greatly heated at times.

Having now described my invention, what I claim as new and desire to secure by Letters Patent is:—

1. The combination with a mold of a cup-shaped guide for loosely receiving the same and forming a closure for one end thereof; a rigidly held lid for closing the other end of the mold, the cup being spaced from the lid and movable relatively thereto; and 125

means for yieldingly pressing the cup and mold and lid into engagement with each other.

2. The combination with a mold of a cup-shaped guide for loosely receiving the same and forming a closure for one end thereof; a rigidly held lid for closing the other end of the mold, the cup being spaced from the lid and movable relatively thereto; and means for yieldingly pressing the cup-shaped guide toward the lid.

3. In centrifugal casting machines, a revoluble basket; a cup-shaped guide loosely carried in the basket; a mold carried in the guide with the bottom of the guide forming a closure for one end of the mold; a lid rigidly held on the basket for closing the other end of the mold, the guide being spaced from the lid and being movable relatively thereto; and means for yieldingly pressing the guide and mold and lid into engagement with each other.

4. In a centrifugal casting machine, a revoluble basket; a mold-carrying cup and a lid carried by the basket, each having an inclined interior surface; a sectional mold received between said cup and lid, said mold being provided with exterior inclined surfaces adapted to be engaged by said interior inclined surface of the cup and lid, the cup having guided movement relatively to the lid; and means for yieldingly pressing the cup and lid toward each other, whereby to yieldingly hold the sections of the mold in engagement with each other.

5. In a centrifugal casting machine, a revoluble basket having an open end; a guide cup in said basket and a lid for the open end of the basket, said guide cup and lid having oppositely disposed interior inclined surfaces; a sectional mold received between said guide cup and lid, said mold being provided with exterior inclined surfaces adapted to be engaged by said interior surfaces of the guide cup and lid, the guide cup being movable on the basket relatively to the lid and carrying the mold with it, and the basket having an opening in the bottom thereof; a plunger for said opening; and means for yieldingly pressing the plunger into engagement with the guide cup in the basket to move the basket toward the lid; whereby to yieldingly press the sections of the mold into engagement with each other, and to permit the unavoidable expansion of the mold sections relatively to each other when the molten metal is poured into the mold.

6. In centrifugal casting machines, a revoluble basket open at its front end; a guide cup loosely received into the basket through said open end; and a lid for said open end thereof, the guide cup being movable relatively to the lid; a mold loosely mounted in the guide-cup between the same

and the lid; a hollow shaft extending outwardly from the rear side of the basket with the interior of the shaft opening into the basket; a plunger mounted in said shaft and adapted to engage the guide cup in the basket; and means for yieldingly pressing the plunger into engagement with the guide cup.

7. A centrifugal casting machine comprising a housing open at its front end and having a sleeve extending centrally from its rear end; a revoluble basket in the housing, said basket having an open front end and a hollow shaft extending from its rear end through said sleeve of the housing in which it has bearing, the interior of the shaft opening into the basket; a guide cup loosely received in the basket and a lid for said open end thereof, the guide cup being movable relatively to the lid; a mold loosely received in the guide-cup between the same and the lid; a plunger mounted in said hollow shaft and adapted to engage the guide cup in the basket; and means connected with the plunger for yieldingly pressing the same into engagement with the guide cup, to urge the same toward the lid; and means for imparting rotation to the basket.

8. In centrifugal casting machines, a revoluble basket open at its front end; a guide cup loosely received into the basket; a lid for said open end of the basket, the guide cup being movable relatively to the lid; a mold loosely received in the guide-cup between the same and the lid; a hollow shaft extending outwardly from the rear side of the basket with the interior of the shaft opening into the basket; a plunger mounted in said shaft and adapted to engage the guide cup in the basket; means for normally holding the plunger out of engagement with the guide cup; and means for yieldingly pressing the guide cup toward the lid.

9. In centrifugal casting machines, a revoluble basket; a guide-cup loosely received in the basket; a mold formed in sections and loosely received into the guide-cup with the bottom of the guide-cup forming a closure for one end of the mold; a lid rigidly held on the basket for closing the other end of the mold, the guide-cup being spaced from the lid and being movable relatively thereto; and means for yieldingly pressing the guide-cup and mold toward the lid, said sectional mold and end closures therefor being provided with means for utilizing the pressures on the guide-cup to also yieldingly hold the sections of the mold in operative relation to each other.

10. In centrifugal casting machines, a revoluble basket; a guide-cup loosely received in the basket; a mold formed in sections and loosely received into the guide-cup, with the bottom of the guide-cup forming a bottom for one end of the mold, the

guide-cup being spaced from the lid and being movable relatively thereto; means for yieldingly pressing the guide-cup and mold toward the lid to close the ends of the mold, 5 and also to hold the sections of the mold in operative relation to each other; and means for automatically releasing said pressure when the mold is not in operation.

11. In centrifugal casting machines, the 10 combination with a mold, of a revoluble support therefor; a lid for the mold and means for holding the same at the front end of the support, the mold being movable toward and from the lid, and the support being arranged to guide the mold in said movements; a plunger for moving the mold; means for automatically holding the plunger normally in inoperative position; and means for yieldingly pressing the same toward the 20 mold, whereby to hold the mold in yielding engagement with the lid.

12. In centrifugal casting machines, a revoluble basket open at its front end; a guide cup loosely received into the basket; a mold 25 loosely received into the guide cup; a lid rigidly held at the open end of the basket, the guide cup being movable relatively to the lid; and means for employing centrifugal force to impart to the guide cup and 30 mold guided movement on the basket toward the lid.

13. In centrifugal casting machines, a revoluble basket open at its front end; a guide cup loosely received into the basket; a mold 35 loosely received into the guide cup a lid rigidly held at the open end of the basket, the

guide cup being movable relatively to the lid, said basket having a chamber at the rear side thereof in communication with the interior of the basket; a plunger mounted 40 in said chamber to move toward and from the guide cup; a spring for normally pressing the plunger in the direction away from the guide cup; and means employing centrifugal force for pressing the plunger toward the guide cup, whereby to yieldingly press the guide cup and mold toward the lid, the lid and guide cup and sectional mold carried thereby being provided with means for utilizing the centrifugal pressure 45 to also yieldingly hold the mold sections in operative relation to each other.

14. In centrifugal casting machines, the combination with a revoluble mold of a lid therefor at the pouring end of the mold 50 having a central opening for the introduction of molten metal and a plurality of openings in the lid equally spaced from said central opening for the escape of excess metal.

15. In centrifugal casting machines, the combination with a revoluble mold of a lid therefor at the front end of the mold, said lid having a central opening for the introduction of molten metal and a plurality of 55 annular slots surrounding said central opening and equally spaced therefrom for the escape of excess metal from the mold, and for creating a vacuum in the mold when rapidly revolving.

In testimony whereof I affix my signature.
WALTER T. JANNEY.
